UNITED STATES PATENT OFFICE.

WILLIAM AUBERLIN, OF NORTHFIELD, OHIO.

AIRSHIP ANCHORAGE.

Application filed August 24, 1927. Serial No. 215,176.

This invention relates to airship anchorages and is in some respects an improvement on or modification of the airship anchorage shown in my U. S. Patent No. 5 1,629,197.

The object of the present invention is to provide improved means for safely mooring an airship to a mast, especially where a strong wind is blowing. In the patent above 10 mentioned, a turntable is shown, provided with a windshield mounted thereon, behind which a mast or tower is provided, to which the ship can be moored. In the present device, the turntable is omitted, and a rotary structure is provided which includes 15 a windshield, and which is pivoted to, the top of a tower, and mounted on wheels so that it can be turned around the tower to various positions according to the direction 20 of the wind. The structure is hollow behind the windshield, and by means of the landing cable the nose of the ship can be drawn into or behind the same, the structure being turned to proper position for 25 this operation.

One form of the invention is illustrated in the accompanying drawings, in which Fig. 1 is a top plan view; Fig. 2 an end elevation; Fig. 3 is a side elevation.

30 In the drawings, 1 indicates a hollow tapered or horizontal pyramidal frame, suitably reinforced by trusses 2 and 3, and shaped to receive the nose of an airship, as shown in Fig. 3. This frame has at its 35 smaller or front end a heavy casting 4, fastened thereto; said part of the frame adjacent to the casting is provided with a covering 5 which serves as a wind break and shield.

40 The hollow frame referred to is connected to and supported by a lower steel framework 6 mounted on wheels 7 which may be driven by motor 8 through gears 9 and 10. The wheels will travel on a circular track 45 or on the ground to set the structure "into the wind"—in proper position to receive the airship.

A ball 11, preferably integral with casting 4 is retained in a socket in the top of 50 a masonry or other tower 12, by means of a ring plate 13, forming a pivot on which

the frame may be turned, serving to anchor the same to the tower. The wheels 7 and the ball 11 form a three point support for the 55 rotary frame.

A line or cable 14 from the dirigible 15 is fastened to a line 16 passing over pulley 17 and thence to a winch 18 which is preferably motor driven and controlled from a cab 19 on top of the structure, from which the motors 8 may also be controlled.

The operation is evident from the description. The motors 8 being operated will drive the wheels 7 and turn the whole structure around the tower to the proper position; and the cable 16 will be connected to a landing cable let down from the ship, which will then be drawn into position with its nose in the frame, behind the windbreak.

The present structure will be found easy 70 to handle and strong to withstand heavy winds and strains, and not liable to be pulled loose or upset. The structure being largely open framework and the round tower will have comparatively little wind pressure itself, and the windshield proper need be only slightly larger than the nose of the ship.

Various modifications in ship, size and construction may be made, within the scope 80 of the following claims.

I claim:

1. An airship anchorage comprising a tower, and a segmental frame standing beside the tower and provided with a windshield at its upper front part and connected to and rotatable around the tower, and provided with means for mooring an airship thereto, the frame having a supporting pivot in front of the windshield, connecting 90 the same at its front end to the top of the tower, and having supporting wheels at the other end.

2. An airship anchorage as set forth in claim 1, the frame comprising an upper, hollow tapered part on which the windshield is mounted, and a lower supporting part mounted on the wheels.

In testimony whereof, I do affix my signature.

WILLIAM AUBERLIN.
